CONVERTIBLE CONTAINER AND CLOSURE
THEREFOR

Stephens Newell, Mentor, Ohio

Application February 8, 1950, Serial No. 143,004

2 Claims. (Cl. 220—40)

1

This invention relates to containers such as are used for jams, cheeses, preserves, beverages and other foods, and more specifically to such containers which, when emptied of their contents, can be utilized as beverage glasses.

It is the primary object of my invention to provide a container and closure therefor, which closure can be utilized as both a coaster and a jacket for the container when it is utilized as a beverage glass.

Another object of my invention is to provide a container and closure of the character described, which can easily and quickly be sealed.

Still another object of my invention is to provide a container and closure of the character described, which is inexpensive to manufacture and is attractive in appearance.

Other objects and advantages of the invention will be apparent during the course of the following description.

In the accompanying drawings, forming a part of this specification, and in which like numerals are employed to designate like parts throughout the same,

Fig. 1 is an elevation of a container and closure embodying the features of my invention, a portion thereof being broken away to show certain details of structure.

Fig. 2 is an elevation showing the container and closure as they appear when the closure is utilized as a coaster and jacket.

Fig. 3 is a transverse cross-sectional view, taken on line 3—3 of Fig. 1 showing the manner of interengagement of the container and the closure.

Fig. 4 is an enlarged sectional view, taken as indicated by line 4—4 of Fig. 3.

Fig. 5 is a view similar to Fig. 4, but showing a modified form of the invention.

Fig. 6 is an enlarged fragmentary longitudinal cross-sectional view illustrating still another form of the invention.

Referring more particularly to Figs. 1—4 of the drawings, the invention is seen to comprise a cylindrical container 1 which is usually and preferably formed of glass, although it could likewise be made of metal or plastic. The container has a suitable bottom 2 and has open end or mouth 3.

The interior surface 4 of the container 1 may be angularly inclined as illustrated, however, the exterior surface 5 is substantially straight or vertical. It will be understood, however, that the exterior surface 5 could likewise be angularly inclined so that the container 1 would be frusto-

2

conical in form, the largest diameter being at the mouth thereof.

On the exterior surface 5 of the container 1 are provided a group of circumferentially spaced cams 6 which extend or project radially outwardly from the surface. I have shown four of such cams although a lesser or greater number could be employed. These cams correspond to and function similarly to a multiple interrupted screw thread.

Each of the cams 6 is in the form of an angularly inclined ridge of semi-circular cross-section, and for purposes of this description, the lower or undersurface of the ridge or cam will be designated by numeral 7 and the upper surface will be designated by the numeral 8.

The cams may lie at an angle of from five to fifteen degrees to the diametrical plane of the container, this angle depending somewhat on the length of the cam 6 and the nature of the materials employed.

It is, however, of critical importance in my invention that the median point of the ridge or cam 6 be located longitudinally midway between the top and bottom of the container so that one end of the cam lies above the mid-point and the other end of the cam lies below the mid-point of the container. For purposes of clarity, I will refer to the end of the cam which lies above the mid-point as the upper end, and will refer to the other end thereof as the lower end.

The container 1 is provided with a cover or closure 9 of cylindrical form which may be formed of any suitable material but which I have illustrated as being made of a synthetic resin. The closure is provided with a closed end or top 10 from which depends an annular flange 11 which forms the wall or skirt of the closure.

Seated against the top 10 of the closure 9 is a sealing ring or gasket 12 which may be formed of some compressible material such as cork or rubber. The gasket lies intermediate the top 10 of the closure and the mouth 3 of the container 1, and serves to prevent spillage or leakage or deterioration of the contents of the container when the closure is secured thereto.

The skirt of the closure may be made of any length commensurate with the function which is performed by it, and normally will extend to at least the mid-point of the container, although it may be longer.

On the interior surface of the flange 11 and preferably formed integrally therewith are a plurality of circumferentially spaced inwardly projecting lugs 13 which in number and spacing

correspond to the cams 6 on the container 1. As best seen in Fig. 4, the lugs 13 are each provided with a flat annular surface 14 which is inclined to the diametrical plane of the container 1 at the same angle as that of the cams 6.

The longitudinal location of the lugs 13 is such that a portion of the surface 14 will be below the upper end of the cam 6 when the closure 9 is loosely mounted on the container 1. Then, when the closure is turned in the direction indicated by the arrow in Fig. 1, the lugs 13 are cammed by the undersurface 7 of the cams 6 and the top 10 of the closure is drawn downwardly to compress the gasket 12 against the mouth 3 of the container, thereby effecting a seal. Thus, the contents of the container are effectively retained therein. To assist the user in gripping and turning the closure, I provide thereon a series of circumferentially spaced ribs or ridges 15.

The container 1 is preferably of such size and shape that it can be used as a tumbler or beverage glass when its original contents have been removed.

In Fig. 2 I have illustrated the manner in which the closure is utilized as a coaster and jacket for the container when the container is used as a tumbler. The closure 9 is removed from its position over the mouth 3 of the container and, instead, is inverted and placed over the bottom 2 of the container, as shown. Due to the fact that the cams 6 are vertically equidistant from the top and bottom of the container 1 as heretofore stated, the closure in its inverted position will permit the lugs 14 to engage the cams 6, although in this instance the lugs are cammed by the upper surface 8 of the cams instead of by the undersurface 7. Thus when the closure is turned in the direction indicated by the arrow in Fig. 2, the closure is drawn up firmly against the bottom 2. The top 10 of the cover 9 then serves as a coaster and the skirt or flange 11 serves as a jacket around the container 1 such as the knitted or leather jackets used with highball glasses. Any condensation which may form on the glass will, of course, be contained by the closure 9, and skirt 11 will assist in insulating the container and thereby maintain its contents either hot or cold as the case may be. The skirt itself will not communicate the temperature of the glass to the hand of the user and thus will be comfortable to the touch.

By properly locating the cams 6 on the container 1, I am able to utilize the closure 9 in either of the two positions illustrated in Figs. 1 and 2 and thus convert the container into a handsome drinking glass. It will be obvious that my invention will also find usefulness whenever liquids are to be transported and subsequently consumed, as at picnics and outings, or in travel.

In Fig. 5, I have shown a modification of my invention in which semi-spherical projections 16 are provided on the closure instead of the lugs 13.

In Fig. 6 I have shown still another modification of the invention in which indents 17 are formed in a closure made of metal, such as aluminum, these indents 17 serving the same function as the lugs 13 or the projections 16.

It is to be understood that the forms of my invention, herewith shown and described, are to be taken as a preferred example of the same, and that various changes in the shape, size and arrangement of parts may be resorted to, without departing from the spirit of my invention or the scope of the subjoined claims.

Having thus described my invention, I claim:

1. The combination of a cylindrical container having an open end and a closed end, uniformly inclined cam elements provided on said container in circumferentially spaced relationship, said cam elements being nominally equidistant from the ends of said container, portions of each of said cam elements extending to either side of the equator of said container, and a closure for said container having portions thereof engageable with said cam elements to releasably secure said closure to either the open end or the closed end of said container.

2. The combination of a cylindrical container having an open end and a closed end, a telescoping closure for said container, and means for releasably securing said closure over either end of said container, said means comprising uniformly inclined camming elements circumferentially spaced on said container in median relationship to the ends thereof, said elements each having parallel camming surfaces disposed toward opposite ends of said container, and cooperating similarly circumferentially-spaced inwardly-extending projections on the wall of the closure.
